US0D1047149S

(12) **United States Design Patent** (10) Patent No.: **US D1,047,149 S**
(45) Date of Patent: ** Oct. 15, 2024

(54) ANALYTE SENSOR DEVICE

(71) Applicant: **ABBOTT DIABETES CARE INC.**,
Alameda, CA (US)

(72) Inventors: **Manuel Luis Donnay**, San Francisco,
CA (US); **Tuan Nguyen**, Dublin, CA
(US); **Louis G. Pace**, San Carlos, CA
(US); **Peter G. Robinson**, Alamo, CA
(US)

(73) Assignee: **ABBOTT DIABETES CARE INC.**,
Alameda, CA (US)

(**) Term: **15 Years**

(21) Appl. No.: **29/946,614**

(22) Filed: **Jun. 10, 2024**

(57) CLAIM

The ornamental design for an analyte sensor device, as shown and described.

DESCRIPTION

FIG. 1 is a top, front perspective view of an analyte sensor device showing our new design according to a first embodiment;

FIG. 2 is a top, rear perspective view thereof;

FIG. 3 is a top, front perspective view of an analyte sensor device showing our new design according to a second embodiment; and,

FIG. 4 is a top, rear perspective view thereof.

The broken lines in the figures illustrate portions of the analyte sensor device that form no part of the claimed design.
